(57) **CLAIM**

The ornamental design for volumetrically efficient alchoholic beverage container, as shown and described.

DESCRIPTION

FIG. 1 is an front elevational view of a volumetrically efficient alchoholic beverage container showing my new design;

FIG. 2 is a side elevational view thereof;

FIG. 3 is a front isometric view thereof;

FIG. 4 is a top plan view thereof; and,

FIG. 5 is a bottom elevational view thereof showing my design.
